UNITED STATES PATENT OFFICE.

CALVIN RETICUS WAID, OF BIRMINGHAM, ALABAMA, ASSIGNOR TO W. C. APPLEBY,
OF BIRMINGHAM, ALABAMA.

GRATE BAR.

Application filed December 26, 1923. Serial No. 682,762.

My invention relates to a new and useful improvement in grate bars of the type in which a rocking assembly bar is adapted to receive a plurality of removable grate segments carrying the fire heads which are interchangeably mounted on the bar so as to make cheap and inexpensive the repair and maintenance of the assembled grate.

The chief object in my present invention is to design both the assembly bar and the grate segments so that they can be easily and cheaply cast; that practically no machine work shall be required either on the segments or the grate bar; and that the segments shall present a minimum interference to the free passage of air upwardly to the fire heads to the end that the entire fire supporting grate surface shall have a maximum air circulation, which air will flow freely both under and over the bars and through the grate openings, which is essential for the rapid and efficient combustion of the fuel.

A further object of my invention is to form all of the segments of a grate alike so that only a single type of segment will be required to be stocked, and to this end my invention contemplates so designing the assembly bar and the attachment means for the shaker bar that the latter can be applied directly to the assembly bar in practically any desired position transversely of the grate. By this arrangement I avoid the casting of certain segments with shaker arms and reduce to a minimum the patterns required and the amount of castings to be stocked.

A further object of my invention is to design an assembly bar as a single bar with its upper edge dropped below the axis of its trunnions and fluted or made concave between the spaced points which receive and center the supporting webs of the grate segments.

A further object is to support a segment solely by thin vertical end webs disposed in the plane in which the segment is rocked so as to oppose only their edges to the flow of air from front to rear of the grate and by utilizing only two supporting webs for a segment I can leave the entire arched space under the fingers forming the fire head practically uninterrupted for the free upflow of air through the interstices between the fingers.

My invention also comprises certain novel details of construction and arrangements of parts both in the grate segments themselves, in the assembly bar, in the shaker lugs and in their manner of attachment to the grate bar.

In the accompanying drawings in which I have illustrated only a typical embodiment of my invention:

Fig. 1 shows an assembly bar with two grate segments assembled thereon, the third being removed to show the shaker lugs attached in plan view.

Fig. 2 is a side elevation of Fig. 1, omitting the shaker lugs.

Fig. 3 is a fragmental view in elevation of one end of the assembly bar showing the shaker lugs mounted thereon with the shaker bar omitted.

Figs. 4 and 5 are sectional views taken on the line 4-4 of Fig. 2, and 5-5 of Fig. 4, respectively. Fig. 6 is a view corresponding to Fig. 5 showing a modified type of segment on a reduced scale.

Similar reference numerals refer to similar parts throughout the drawings.

In the embodiment of my invention illustrated, I show an assembly bar 1 formed by a vertical web-like casting having a shoulder 2 extending along its base and terminating in a bottom concave face 3 for lightness and strength. The bar at intervals on each side is cast with spaced ribs or shoulders 4 which rise from the shoulder 2 vertically and extend preferably to the top edge of the bar. These shoulders 4 are arranged opposite each other on both sides of the bar and in each shoulder is formed a vertical concave groove 5 which terminates at its bottom in a notch 6 in the shoulder 2, which notch slopes outwardly and merges into the side of the shoulder 2 a little below the upper edge thereof. The shoulders 4 are arranged in groups of two pairs for each grate segment, the units of each group are equidistantly spaced from the next adjacent groups so that the segments can be interchangeably mounted therein without changing the grate surface. The upper edge of a bar between the pairs of shoulders is beveled to a sharp edge and cut down on a concave as indicated at 7. This fluting of the upper edge of the assembly bar throughout its length greatly increases the air circulation space without weakening the bar. At each end

the bar has a rising portion 8 which carries an end trunnion 9, the axis of which lies almost in the plane of the top edges of the shoulders 4. This arrangement causes the 5 bar to underhang substantially below its axis and makes it better balanced for its shaking operation.

Inasmuch as the several grate segments, which are generally indicated by the number 10, are alike only one need be described.

Referring more particularly to Figs. 2, 4 and 5, it will be seen that each segment comprises parallel vertical transverse end walls 11 which near their ends are connected to their vertical parallel webs 12, which extend from front to rear of the grate and drop below the level of the end walls 11 so as to provide supports 13 which are formed 20 with a bottom vertical slot 14 that enables the supports to be mounted astride an opposite pair of shoulders 4 of the assembly bar. Preferably the supports are strengthened by thinner webs 15 which extend from near the 25 lower ends of the support on an outward curve to points of juncture with the walls 11. The slot 14 is notched out or enlarged at 16 so as to avoid too close a fit with the shoulder 2 of the bar, it being noted that 30 the supports 13 will pass freely downwardly into the grooves 5 in the shoulders 4, which shoulders receive the supports between them on each side and thus bring the segment to position, centering it and holding it against 35 lateral displacement while leaving it free to be lifted vertically from the bar. The notches 6 at the bottom of the grooves 5 leave ample clearance so that fins or projections often present on the casting will not 40 prevent the segments properly seating on the bar. The webs 12 are arched overhead and are provided on their inner and outer faces with laterally extending teeth 17 and 18, these teeth being of such length and so 45 spaced as to afford ample support for the fire bed while leaving a maximum number of uniformly distributed spaces for the free and unobstructed passage of air upwardly therethrough to the fire.

50 In the drawings I show the end walls 11 connected by a central web 19 which is arched overhead like the end walls 12 but which is a much thinner web and terminates just below the bottom beveled edges of its 55 teeth 20, which, as shown, correspond to teeth 18. In practice the grate segments are made in different widths to suit fire boxes or furnaces of different sizes, it being only essential that the segment shall comprise 60 two end webs 12 which may be combined with as many middle webs 19 as desired. As the width of the segments vary, the end webs 12 can be drawn nearer together or farther apart and the fingers 17, 18 and 20 65 can be lengthened or shortened so as to

maintain approximately the clearances shown. I have illustrated the segment with the middle web as it represents the more complex structure.

It will be especially noted by reference to Figs. 2 and 5 that the ends of the walls 11 are cut away on an ogee curve beyond their point of juncture with the webs 12, and that between the webs 12 the bottom edges of the walls 11, when the segment is 70 at level, will stand high above the fluted top level of the assembly bar, thus affording a direct, free and practically unobstructed 75 passage for the air to flow from front to rear of the grate between the bars 1 and the fire heads of the grate segments supported thereby. In this way I get a practically unobstructed flow of air which gains access 80 freely to the opening between all of the fingers 17, 18 and 20 and makes the grate capable of maintaining a very hot fire while the widely distributed and ample updraft of cool air through the grate will prevent 85 burning out of grate segments. The webs 15 afford ample reinforcement for the relatively thick end walls 11 of the grate segment and enable it to withstand the strain of breaking the clinkers as the grate is 90 rocked. Preferably the under edges of the intermediate web 19 are beveled.

To facilitate the attachment of shaker elements, not shown, I provide for each assembly bar a pair of shaker lugs 21 and 22 which at their upper edges have jaws shaped to fit about and grip the shouldered bottom 100 edge 2 of the bar. Bosses 23 are cast in the lugs below the bar and receive bolts 24 which serve to clamp the jaws in interlocked engagement with the assembly bar. The lug 22 of each pair is provided with a laterally offset dependent arm terminating in a perforated ear 25 and its companion lug 21 is provided with a similarly offset arm terminating in a perforated ear 26. These ears, when the lugs are clamped in position on 105 the bar by the bolts 24, will be sufficiently spaced to receive a shaker bar, not shown, which is adapted to be bolted to the lugs through aligned apertures in the ears 25 and 26. The arms are braced by suitable 110 webs to strengthen them for their duties and the advantage of offsetting them is that the lugs, by reversing or by shifting them lengthwise of the bar between the shoulders 4, can bring the ears 25, 26 into any desired 115 transverse position to receive a shaker bar. This is of great advantage in that it enables me to place the shaker bars wherever desired, both for front and back sections of the grate and to bring them through any 120 openings already provided in the fire box front.

As observed in Fig. 5, all of the teeth have the greatest depth at their supporting web and have their under edges sharply 125

beveled. The various webs and teeth are shaped so as to have proper draft to be drawn from the sand.

In operation, the assembly bars are mounted transversely in the manner well understood in the art on suitable supports and the individual grate segments 10 are mounted astride the bars with their supports 13 fitting into the groove-ways 5 on the shoulders 4 and being thereby spaced and centered on the assembly bar. The shaker lugs are then applied to the assembly bars in proper alignment with the opening or openings in the furnace front and the shaker bar or bars are connected to the lugs of the group of assembly bars which are to be shaken together. The grate as thus assembled interposes only the narrow relatively thin webs 13 and end walls 11 to the free longitudinal flow of air from front to rear through the furnace, the air currents being free to flow over the assembly bars due to the spacing of the grates above the fluted top edge of the bars. When any grate segment is damaged it can be quickly replaced by clearing the fire from about it and lifting it vertically from its assembly bar and then dropping a new segment astride the bar to replace it. By providing shaker lugs and attaching them to the assembly bar I can make all segments alike, though obviously the segments will be made in sizes so that they can be assembled to make any desired size of grate surface.

Though I have described with great particularity the details of the embodiment of the invention herein shown, it is not to be construed that I am limited thereto, as changes in arrangement and substitution of equivalents may be made by those skilled in the art without departing from the invention as defined in the appended claims.

Having thus described my invention, what I claim as new and desire to secure by Letters Patent, is:—

1. In a grate, an assembly bar having rocker trunnions, a plurality of duplicate grate segments having spaced supporting webs detachably mounted on said bar, and a shaker attachment clamped to the base of said bar between the supporting webs of said segments.

2. In a grate as described in claim 1, the shaker attachment being adapted for adjustment lengthwise of the assembly bar between the webs of a segment.

3. In a grate, an assembly bar having end rocker trunnions and an enlarged base, a plurality of individual grate segments having spaced supporting webs mounted on said bar, and shaker lugs clamped to the base portion of said bar and adjustable lengthwise thereon between the segment webs.

4. In a shaker grate, a unit comprising an assembly bar having an enlarged base, and

cast grate segments mounted on said base, in combination with shaker lugs comprising castings with right and left hand laterally offset perforated ears adapted to receive between them a shaker bar, said lugs being reversible and having holes for clamping bolts disposed below the assembly bar when the lugs are mounted thereon.

5. In a grate, a transverse assembly bar having end trunnions and having a relatively thin body portion enlarged at its base and provided with spaced shoulders forming segment spacer elements arranged in opposite pairs on its vertical sides and rising vertically from said base substantially to the top of the bar, in combination with grate segments having their vertical supporting webs slotted to straddle said bar and coact with said spacer elements to be thereby centered on the bar free for independent vertical removal and replacement.

6. In a grate according to claim 5, the assembly bar being reduced to form channels between the shoulders and having its base notched at the bottom of each of said channels, as and for the purposes described.

7. In a grate according to claim 5, the segment supporting webs being set at right angles to the bar and adapted to fit slidably into the grooves formed between said pairs of shoulders disposed oppositely on the sides of said bar, each supporting web having its sides at the bottom end of the slot cut away, the enlarged base of the bar being notched out opposite the said cut away sides of the web slot when the segment is mounted on the bar.

8. A grate composed of a series of transverse rocking assembly bars and supporting elements therefor, and a series of similar grate segments mounted on each assembly bar and having means to center and hold them thereon against lateral displacement, each segment having a fire head with thin tooth supporting webs which taper downwardly and stand in vertical parallel planes from side to side of the grate, the outer webs of said fire heads being downwardly extended and having their bases transversely notched to straddle the assembly bar and support the entire fire head, and intermediate webs of said fire heads being in a plane substantially above the top level of the assembly bars.

9. A grate in accordance with claim 8, in which the segments have solid ends connecting the several webs and depending substantially below the bottom level of the teeth and the upper edge of the assembly bar is cut away between the points of engagement with the supporting webs of the grate segments to bring it below the level of said solid ends.

10. A grate in accordance with claim 8, in which the top edge of the assembly bar is

made concave throughout its portion between the points of engagement with the end supporting webs of each grate segment.

11. A grate comprising a plurality of 5 rocking assembly bars and supports therefor, each bar having spaced vertically grooved centering shoulders for grate segments and having its upper edge concave between such shoulders, and a plurality of 10 duplicate grate segments, each having a fire head and thin transverse vertical webs bearing teeth at their upper ends, the end webs

only being elongated and having their bases transversely notched to straddle the assembly bar shoulders and to be supported thereby with the entire fire head standing substantially above the top level of the assembly bar thereby to permit a free flow of air from front to rear of the grate between the successive fire heads and assembly bars 15 thereof.

In testimony whereof I affix my signature.

CALVIN RETICUS WAID.
